UNITED STATES PATENT OFFICE.

CORNELIUS VANDERBILT, OF NEW YORK, N. Y.

TENDER FOR LOCOMOTIVES, &c.

SPECIFICATION forming part of Letters Patent No. 781,699, dated February 7, 1905.

Application filed September 12, 1904. Serial No. 224,061

To all whom it may concern:

Be it known that I, CORNELIUS VANDERBILT, a citizen of the United States, residing in the borough of Manhattan, city and State of New York, (having a post-office address at 30 Pine street, in said borough,) have invented certain new and useful Improvements in Tenders for Locomotives, &c., of which the following is a full and true description.

10 My invention relates to tenders for the carrying of water and fuel, and is an improvement on the tenders set forth and described in Letters Patent No. 681,760, granted to me September 3, 1901, and Letters Patent No. 15 747,280, granted to me December 15, 1903.

The objects of my invention are, first, to make a simple and economical form of water-tank which shall have a low water-intake and large capacity; second, to shorten the length 20 of the tank without increasing its height or decreasing its capacity; third, to improve the construction of the water-tank; fourth, to improve and simplify the accessories for the car; fifth, to improve the construction of the fuel-hood. I obtain these several results by means 25 of the construction hereinafter described and which constitutes a preferred form or embodiment of my invention.

In the drawings which accompany this specification and form a part thereof, Figure 1 is a side elevation of a body of a locomotive-tender embodying my improvements, a part of the casing being broken away to show the interior 30 baffle-plates and stiffening members. Fig. 2 is a top view of the tender shown in Fig. 1. Fig. 3 is a rear elevation of the same. Fig. 4 is a similar view to Fig. 3, but showing a modified form of tank. Fig. 5 is a front elevation of the tender illustrated in Fig. 1.

40 The same reference characters refer to the same parts in all figures.

A designates the water-tank, which is elliptical in cross-section and has its major axis arranged in a horizontal plane. I have not 45 shown the trucks which carry the tank, since they form no part of my invention. I may use trucks similar to those set forth and described in my Letters Patent above referred to or others of approved design. The tank 50 is provided with a water-intake a^3 , and on

each side of the intake I provide drain-troughs a . These drain-troughs are made of trough-shaped pieces of sheet metal and are riveted at one edge to the casing of the tank. They serve to catch any water which may overflow 55 from the intake a^3 or which may be spilled around the same. The tank is also provided with handles a^2 and with running-boards M, which are supported by brackets M in the ordinary manner. At the front end the tank 60 is cut away at a^4 , a^5 , and a^6 to provide room for the coal-hood B. The coal-hood is formed at the rear by a vertical wall b' , which is, in effect, a continuation of the surface a^4 of the water-tank. The rear wall b' carries handles 65 b , which can be used by the attendants in climbing onto and off the hood.

b^2 denotes the side walls of the hood and are spaced apart a distance equal to the major axis of the water-tank. The rear end of the 70 coal-hood is provided with sliding doors b^3 , which have handles b^4 .

N is a front platform on which the fireman may stand. The front wall of said platform has an opening to receive the ordinary bumper O. 75

The underframing of this car consists, primarily, of two longitudinal draft-sills E, which are connected directly to the shell of the water-tank and which have mounted between them at each end the ordinary draft-rigging. 80

In a tender of this kind it is desirable to have a large water capacity and also a low water-intake, and to combine these desirable features I mount my tank very low and provide a recess F at the rear end of the tank 85 for the reception of the draft-rigging G. This recess is made by bending the lower part of the casing inward, as at f' . By means of this recess I am enabled to mount the draft-rigging between the end of the draft-sills and 90 without sacrificing but very little of the capacity of the tank.

The tank A is made elliptical, for the reason that such a tank has a larger capacity than circular tanks of the same height and has a 95 lower center of gravity than a circular tank of the same capacity. It will be seen that by recessing the tank at F and lowering the bottom of the same below the top of the draft-rigging and by making the tank elliptical I 100

am enabled to secure maximum capacity with minimum height. The recess F allows me to attach the shell of the tank A directly to the draft-sills without removing the draft-rigging from between the sills. I am thus enabled to mount the draft-rigging where it will have the maximum strength and where it will correspond in height with the draft-rigging in common use. I have only shown a recess F at the rear end of the tank. However, it is obvious that such a recess may be provided at the front end of the tender without departing from the spirit of my invention.

15 In order to prevent the water in the tank from acquiring great momentum when the train is suddenly started or stopped, I provide the baffle-plates K, K', K², K³, and K⁴. The plate K' is mounted on the bottom of the tank and is provided with a suitable opening p (see Fig. 5) to allow the water to drain from one compartment to another, as will be readily understood. This plate is semi-elliptical in form and is attached at its lower and side edges to an angle-iron k, which in turn is riveted to the shell of the tank. The baffle-plates K and K² are similar to K', but are attached to the top of the shell. The baffle-plate K³ is in the form of a slat and is located midway between the bottom and the top of the tank. This plate is secured to an angle-iron stiffening member k', which is riveted to the shell of the tank and extends entirely around the inside of the same. This stiffening member is very desirable in an elliptical construction of this kind, and I may provide several such members located throughout the length of the tank and may employ them in connection with baffle-plates or independently thereof. The plate K⁴ is suspended from the top wall a⁵ of the tank. The baffle-plate K⁵ is attached at its top to the plate a⁶ and serves as a support for the bottom of the coal-hood and as a baffle-plate. It is obvious that the alternate arrangement of the baffle-plates on the top and bottom of the interior of the tank, in connection with the baffle-plate K³, arranged midway between the bottom and top of the tank, will allow the water in the tank to acquire a limited motion when the train is started or stopped without acquiring objectionable momentum.

While I have described and shown my improvements applied to the tank of a locomotive-tender, I am aware that the improvements are equally applicable to tank-cars, and I wish to include such cars within the scope of my invention, and while I have described my invention specifically and in detail I am aware 60 that there are various modifications which can

be made in the same by skilled mechanics, and I wish to include all such modifications which fall within the scope of my claims.

What I claim is—

1. In a tender or similar vehicle, an elliptical tank, having its major axis transverse of the vehicle, substantially as described. 65
  2. In a tender or similar vehicle, an elliptical tank having its major axis transverse of the vehicle, and a plurality of stiffening members within the tank, substantially as described. 70
  3. In a tender or similar vehicle, an elliptical tank having its major axis transverse of the vehicle, and a fuel-hood mounted on said tank, substantially as described. 75
  4. In a tender or similar vehicle, an elliptical tank having its major axis transverse of the vehicle, and a fuel-hood mounted on the front end of the tank and having a width the same as that of the tank, substantially as described. 80
  5. In a tender or similar vehicle, a tank having an elliptical body and rear end and semi-elliptical front end, having a coal-hood mounted thereon, substantially as described. 85
  6. In a tender or similar vehicle, an elliptical tank, the major axis of which is transverse of the vehicle, and a plurality of semi-elliptical brace-plates within the tank, substantially as described. 90
  7. In a tender or similar vehicle, a tank having a series of baffle-plates placed alternately at the top, midway between the top and bottom, and at the bottom of the tank, substantially as described. 95
  8. In a tender or similar vehicle, a tank and a transversely-disposed stiffening-ring within the tank and continuously secured to the interior thereof, and a baffle-plate located intermediate the bottom and top of the tank and secured to the stiffening-ring, substantially as described. 100
  9. In a tender or similar vehicle, an elliptical tank having its major axis in a horizontal plane, semi-elliptical baffle-plates secured to the bottom and to the top of said tank, substantially as described. 105
  10. In a tender or similar vehicle, a tank provided with an intake and having drain-troughs on each side of the intake formed of bent metallic strips secured to the casing of the tank, substantially as described. 110
- In testimony whereof I have signed my name to this specification in the presence of two witnesses. 115
